(57) **CLAIM**

I claim the ornamental design for an elastic rope-type abdominal exerciser, as shown and described.

DESCRIPTION

FIG. 1 is bottom plan view of an elastic rope-type abdominal exerciser showing my new design.

FIG. 2 is a top plan view thereof.

FIG. 3 is a rear elevation view thereof.

FIG. 4 is a front elevation view thereof.

FIG. 5 is a left side view thereof.

FIG. 6 is a right side view thereof; and,

FIG. 7 is a perspective view thereof.
